(57) **CLAIM**

The ornamental design for a bicycle as shown and described.

DESCRIPTION

2. Bicycle

2.1 is a right side elevation view of a bicycle embodying my new design;

2.2 is a rear and left side perspective view thereof;

2.3 is a front and left side perspective view thereof; and

2.4 is a right side elevation view thereof.

The broken line showing of various portions of a bicycle are provided for the purposes of illustrating environmental structure and form no part of the claimed design.
